CONFECTION PACKAGE AND TOY
STRUCTURE

Robert L. Batchlet, Cleveland Heights, Ohio

Application May 4, 1950, Serial No. 160,072

3 Claims. (Cl. 99—180)

1

The object of my present invention has been to produce certain novel packaging and toy structure vending means for facilitating the merchandising of bubble gum, candy, and the like.

In its preferred form the invention contemplates the provision of a foldable box or container on the bottom or other suitable portion of which are carried a series of loops after the manner of formation of the loops of a cartridge belt. The box or container may be made of paper, or like material of suitable weight, preferably light cardboard in character, and the loops carried by the container are designed to receive bubble gum, chocolate candy or similar units of vendable nature which are shaped in the form of bullets and individually wrapped in tin foil or some suitable impervious material. In addition the box or container is so made that the portions thereof which carry the individual gum or candy units may be separated from each other with facility by reason of the provision of lines of weakening or perforations between the sections of the bottom or like portion on which the vendable units are mounted. Again, it is contemplated that the various portions of the container which are folded together to provide a box-like form may be readily separated from the bottom portion which carries the bubble gum, candy, or similar units, so that when so separated the bottom or base portion will resemble to a large extent a section of a cartridge belt. Carried by the said bottom portion which supports the vendable articles are certain attachment or clamping pins which are detachably engaged therewith and which enable the separated bottom or section of the container having the loops partly encircling the cartridge-like candy or gum units to be detachably secured to the belt of a child who has purchased one of the packaging holders or containers of my invention. Provisions are made on the commodity carrying section or base of the container for adjusting the clamping pins or members which are detachably mounted in place so that as a loop carrying section of the base is torn off the clamping members may be shifted to another portion of the said base which may still carry the remaining ones of the gum or candy units vended by the packaging means.

In the carrying out of my invention along the lines of the provisions above described for the packaging container I obtain an interesting construction of container means which is susceptible of being used a considerable period after its container construction is done away with, the packaging articles being especially attractive for use

5 by children after the manner of a section of a cartridge belt and affording an excellent way of carrying the gum, candy or confection bodies which are originally supplied in the closed container, after the container has been opened and the base section with the confection carrying means attached to a belt or the like.

10 A full understanding of my invention will be had upon reference to the following detail description, and to a preferred embodiment of the invention as illustrated in the accompanying drawings.

15 In the drawings:

Figure 1 is a perspective view showing a merchandising container or box embodying the invention.

20 Figure 2 is a view showing the various portions of the container of Figure 1 laid out flat to bring out the construction of the base or bottom section which is equipped with the commodity carrying or supporting loops, and the other portions of the container which are folded together to bring the same into the box-like form illustrated in Figure 1.

25 Figure 3 is a plan view which shows the side, end, and top portions of the container detached from the base or loop equipped portion in the condition in which the said base or bottom section may be used after the manner of a cartridge belt section attachable to the belt of the child or other person. In this view the confection bodies are bullet shaped and are shown mounted in the loops on the base section.

30 Figure 4 is a bottom plan view of the structure illustrated in Figure 3, the end clamp or suspending members being shown as mounted on the said structure for engageably cooperating with a belt such as shown in Figure 6, to support the several units in the loops of the section, after the manner of a cartridge belt.

35 Figure 5 is a vertical sectional view taken about on the line 5—5 of Figure 3.

40 Figure 6 is a view similar to Figure 5, taken on the line 6—6 of Figure 3, a belt shown in section.

45 Figure 7 is a perspective view of the base section carrying the confection body as when it has been shortened by detachment of two of the end sections after the bullet-like confection bodies of the latter have been used and the loops thereof emptied and therefore of no further use. In this view the fin-like clamping or supporting members for the reduced size base section have been adjusted to new positions on the latter after detachment of the end sections, and engage a belt.

50 Referring now to the specific and preferred

construction of my invention, as illustrated in the drawings, it is notable that I provide a container of the general type shown in Figures 1 and 2, the same comprising the bottom confection holding section 1 the sides 2 having their attached foldable flaps 3 foldable upon the fold lines 3a, and the ends 4. Said ends 4 are slightly different in that one of them is provided with a short flap member 5 and the other carries the top or cover section 6 of the container. Said cover section may be formed with the flaps 7 and 8 at its free ends, the flap portion 7 adapted to engage the opposite end 4 of the container and the flap 8 adapted to underlie the bottom or section carrying section 1 of the container when the latter is folded in condition of Figure 1. Either or both of the members 7 and 8 may have mucilage or other adhesive applied thereto for sealing action after common practice so that the container may be effectively sealed closed at the time of its vendition to the purchaser.

On the section supporting base or bottom section 1 of the container I apply a strip of material designated 9 which is formed into small loop members 10 at intervals in its length and which is secured to the part 1 by suitable adhesive between the member 1 and portions of said strip 9 located intermediate of the several loop parts 10.

The confection carrying section 1 is divided into sections by means of perforations or weakening lines cut therein, as designated at 11, so that as seen in Figure 3 there are practically five of the sections mentioned, each carrying a loop 10 for confection body. Of course, if the container is made longer than that which is illustrated in the drawing there may be a larger number of the sections which are designated 1a for the purposes of this description. Or again, if a container of lesser size than shown in Figure 2 is desired, there may be a less number of loops 10 and a corresponding less number of the sections 1a. Each of the sections 1a of the loop carrying section 1 is provided with a notch 12 at the lower edge portion thereof and with a small aperture 13 opposite said notch and adjacent the upper edge thereof. The purpose of the parts 12 and 13 is to enable detachable interlocking engagement with each section 1a by a supporting pin or spring clamp member 14 having the inner side thereof forming the clamp member element for engaging with or over a belt which may be worn by the child who has purchased the container of my invention and has placed the section in the condition in which it is shown in Figure 3 for use as a cartridge belt section, so to speak.

The lower loop portion of the clamping member 14 engages over the lower edge of the section 1a of the base section 1 with which it cooperates and the clamp members are normally mounted on the end sections 1a when the container is supplied to the purchaser. The upper end portion of each clamp member 14 at the rear side of sections 1a carrying the loops 10 is interlocked with the material of the section 1 by passing through the aperture 13.

It will be observed from Figure 3 of the drawings that each of the loops 10 has inserted therein the confection or other particular vendable commodity which is shaped in the form of a bullet and which is preferably covered by tinfoil to somewhat enhance the resemblance of the unit to a bullet. The resemblance may be somewhat superficial because the confection bodies may be flattened on their inner sides in-

stead of completely round, though this is not a material matter so far as my invention is concerned.

The manner of use of my invention will be apparent from the foregoing in the light of the following description.

When the commodities to be sold in the container of the invention are packed properly they will be enclosed fully in the box-like structure of Figure 1 and sold in such condition. The child or other purchaser who buys the container, upon receiving the same, will tear off the end sections 4 at the end of the base section 1 and also tear off the side sections of portions 2 at 15 the upper and lower longitudinal edges of the section 1. This brings the section supporting section 1 of the container to the condition of Figure 3 and thereupon the person purchasing the article described can readily mount the section 1 upon his belt by engaging the clamp members 14 over the belt and pressing the same downwardly to fully engage the latter. Of course, under the above condition, the confection units 15 are readily accessible and, as stated, 20 they may be gum, chocolate, or other candy bodies, or the like, wrapped in tinfoil. When the user has used or eaten or chewed the end confection bodies 15 he can detach the end sections 1a from the base section or main body 25 section 1 and adjust the clamping members 14 from the positions shown in Figure 3 of the drawings to engage the slots 12 and apertures 13 of the next adjacent sections which have not yet been emptied of the confections contained 30 in the loops thereof.

The foregoing sets forth generally the manner of use of my invention and it will be seen that an attractive method of merchandising confections of different kinds is supplied by means of 35 the invention, as well as a method which enhances the interest of the purchaser who would usually be a child susceptible to being entertained by the manner of use of the invention.

The strip of material 9 has tear lines of weakening at points 9a aligned and coinciding with the like portions 11 of the base or carrying section 1.

My invention contemplates also the use of the units seen in Figures 3, 4, and 7 in unit with the container, or separately therefrom.

The clamping members 14 may be united to the container, as shown in Figure 2, when the container and contents are assembled, or laid in the container as seen in dotted lines in Figure 1, when the package is sold. The members 14 may 50 also be engaged with the belt portion of pants.

Having thus described my invention, what I claim as new and desire to secure by Letters Patent of the United States is:

1. A combination confection containing package intended for children's use as a toy cartridge belt simulating structure, comprising a container body for pre-conditioning the structure for sale and including a bottom confection holding section and parts including a cover for at least partially enclosing the contents of the container, confection carrying elements in the form of loops on the bottom section, and bullet shaped confections inserted in and supported by the loops, the container being made of tearable paper material 60 and provided with weakened tear lines intermediate the enclosing parts and bottom holding section, enabling detachment along such lines of the said parts and cover from the bottom confection holding section.

2. A package and toy structure as claimed in

claim 1 in which the bottom section is divided into portions each separated from the other by tear lines, and each said portion supporting one of the loop carrying elements and its supported confection whereby as each confection is used, the loop and its supporting portion may be torn off the bottom section to reduce its size.

3. A package and toy structure as claimed in claim 1 in which the bottom section is divided into portions each separated from the other by tear lines, and each said portion supporting one of the loop carrying elements and its supported confection whereby as each confection is used, the loop and its supporting portion may be torn off the bottom section to reduce its size, each of the portions of the bottom section separated by said tear lines being formed at one edge with a notch and near its other edge with an aperture adapted to receive a clamping member for connecting the latter thereto.

ROBERT L. BATCHLET.
